UNITED STATES PATENT OFFICE.

CHARLES H. FISCHER, OF CINCINNATI, OHIO, ASSIGNOR, BY MESNE ASSIGNMENTS, TO THE CORCORAN-VICTOR COMPANY, OF CINCINNATI, OHIO, A CORPORATION OF OHIO.

ELECTRIC CONNECTOR.

1,294,644.

Specification of Letters Patent. Patented Feb. 16, 1919.

Application filed July 17, 1914. Serial No. 351,581.

To all whom it may concern:

Be it known that I, CHARLES H. FISCHER, a citizen of the United States, residing at Cincinnati, in the county of Hamilton and 5 State of Ohio, have invented certain new and useful Improvements in Electric Connectors, of which the following is a specification.

It is the object of my invention to provide an electric connector of novel construction especially adapted for vehicle electric lamps. Vehicle electric lamps as usually constructed comprise an outer casing and a reflector received within the outer casing, 15 there being a space between the reflector and casing. The casing is usually provided with a connector with which an electric conductor from the source of power is releasably connected and the reflector is usually provided 20 with a connector for receiving the light-bulb, the electric connection between said connectors being located in the space between the casing and reflector.

It is one of the objects of my invention 25 to provide electric connectors which are compact in length, so as to occupy little lengthwise space, in order that the rear ends of the reflector and casing may have little space between them. It is the object of my 30 invention, further, to provide insulating means in an electric connector of the character mentioned which occupies little lengthwise space; further, to provide novel means for insulating the terminal post of the electric connector from the supporting tube thereof; further, to provide novel means for 35 resiliently holding the plug in the connector and forming electric contact with the periphery of the plug over a wide area; and, further, to provide novel means for securing 40 the flexible electric conductor to the longitudinally movable post of the electric connector, and the invention will be further readily understood from the following description and claims, and from the drawings, 45 in which latter:

Figure 1 represents a longitudinal axial section of a vehicle electric lamp, in which my improved electric connectors are exemplified.

Fig. 2 is a perspective view showing the parts of my improved device in separated relation.

Fig. 3 is a front end elevation of my improved device.

Fig. 4 is a rear end elevation of the same.

Fig. 5 is an enlarged central longitudinal section of the same; and

Fig. 6 is a sectional detail on a line corresponding to the line 6—6 of Fig. 5. 60

The casing of the lamp is indicated at 11, the reflector at 12, and the door at 13. The door is provided with a glass 14, or other suitable device through which the rays of light from the reflector are projected. The 65 reflector is arranged to be suitably secured in place, as to the casing, by means of screws 15, the door being shown hinged to the body by means of hinges 16. Other usual or suitable means may be employed for securing 70 the reflector in place for projecting into the casing. The reflector is exemplified as a parabolic reflector, the casing being similarly formed, there being a space 17 between the reflector and casing. 75

The reflector is, at its rear end, provided with a central aperture 21 which is coincident with the longitudinal axis of the lamp and with the line of the principal axis of the reflector. An annular flange 22 is located about the aperture, and is shown as on a flange-piece 23 provided with a laterally extending annular wing 24, by means of which the flange-piece is secured to the reflector so as to extend preferably rearwardly therefrom, the securing being accomplished, for instance, by means of soldering, 80 brazing or heat welding.

A socket-tube 25 is arranged to slide lengthwise in the flange and has a plug securing means 26 at its forward end, which is arranged to receive the plug 27 of a light-bulb 28. 90

These plug-securing means comprise slots 31 which extend lengthwise of the tube and 95 have lateral extensions 32 between which and the slots proper lips 33 are located, forming bayonet connections. The plug is provided with radially extending pins 34 arranged to be received in the slots 31, the pins being arranged to be received within the lateral extensions of the slots behind the lips 33 and to be pressed forwardly for holding the parts in place. 100

The plug is in practice usually cylindrical 105 in form. In order to hold the plug firmly in place and to make good electric connection therewith, I provide the socket-section of the socket-tube with laterally extending wings 36, the front and rear edges 37, 38, 110 of which are free of attachment to the socket-section, one of the lateral edges 39

of said wings being integral with said socket-section. These wings are preferably formed by providing laterally extending slots 40 extending laterally from the slots 31 for severing said wings at their inner ends from the socket-section, one of the lateral edges of the wings in the present exemplification being formed by one of the walls of the slots 31.

10 These wings are curved resilient wings and are bent inwardly slightly, whereby the plug contacting portions thereof are located within the longitudinal projection of the socket-section, as shown in Fig. 3. When 15 now the plug is inserted in the socket, these wings are pushed outwardly by the plug, and, being slightly resilient, they make close contact with the plug while the same is located in the socket, for securely holding the 20 plug in position and making good electric contact therewith. These wings extend laterally about the annular periphery of the plug and occupy little space lengthwise of the connector, while at the same time they 25 make contact with a considerable portion of the area of the plug for holding the same securely in position and preventing rattling thereof and for making good electric contact therewith over a wide area.

30 A hard fiber washer 45 is secured to the tube. This hard fiber washer is an electric insulating washer and is formed as a thin hard fiber disk occupying little lengthwise space of the tube. These hard fiber washers are preferably punched out of sheet hard fiber and form effective, compact and economical insulating means for the purpose and in the relation described. In the present exemplification I have shown the 40 same secured in place by forcing a portion of the metal of the tube inwardly at the end of the hard fiber washer, shown accomplished by striking out lips 46, 47, out of the body of the tube and bending the same 45 inwardly against the respective ends of the hard fiber washer for positioning the same lengthwise in the tube. My improved construction permits an electric connector of substantially less length to be formed than 50 when employing rubber insulation in the relations that said rubber insulation has been heretofore employed in electric connectors, and provides a more simple and durable structure not liable to fracture.

55 A longitudinally movable electric terminal post 48 is movable lengthwise through the hole 49 of the hard fiber washer, and has a spring 50 thereabout between the washer and a head 51 of the post, for normally 60 pushing the post toward the central terminal 52 of the electric light-bulb 28 when the latter is located in the plug-securing means. The head 51 is shown as a ring received against a shoulder 53 about a reduced end

54 of the post and held in place by spreading the outer end of said reduced end, as shown at 55, when the parts have been assembled.

An inner tube 61 is preferably provided as a bearing for the terminal post. This inner tube is secured in the hole 49 of the hard fiber washer by providing this tube with a reduced portion 62, forming a shoulder 63 received against one side of the hard fiber washer, the reduced end of the tube being received through the hole in the washer, the outer end of this reduced portion of the tube being spun about the outer end of the hole in the washer, as shown at 64, for firmly securing the tube in place. The spring is shown as a spiral spring received between the inner end of the tube and the head of the electric terminal post. The outer end of the electric terminal post is shown formed as an enlargement 65.

The longitudinally movable terminal post extends for its major portion outside the thin insulating washer the major outwardly projecting portion being spaced from the socket-tube by an annular insulating space 66.

A flexible electric conductor 67 is provided with an insulating cover 68, the outer portion of which is formed in usual manner as a fabric covering. The enlargement 65 has a hole 69 therethrough sufficiently large to receive the covering of the conductor, so that the strain of any bending of the flexible electric conductor at the post is received primarily by the insulating covering for preventing crystallization of the electric conductor proper, and thereby preventing the breaking of the electric conductor. The core of the electric conductor is reversely bent, as shown at 70, and is received in a slot 71 in the enlargement of the post, in which it is suitably secured, as by means of soldering, shown at 72. By these means the inner end of the inner electric conductor is secured to the electric bulb terminal.

The rear end of the socket-tube is provided with a slot 73 through which the flexible electric conductor passes from the enlargement 65.

The socket-tube is arranged to be adjustably positioned in the flange, as by providing the flange with a set-screw 74 having threaded connection through the flange and making contact with the socket-tube for securing the socket-tube in any position of lengthwise adjustment for placing the electric bulb in proper focal position and securing the same in such position.

An outer connector similar to that hereinbefore described may be provided for receiving the usual plug 78 of an electrical connection 79 from a usual source of electric energy, this plug in practice being usually a

plug having an annular periphery similar to the plug 27, and provided with pins 34' similar to the pins 34 and having a central terminal 52' similar to the terminal 52. The outer connector being similar to the connector hereinbefore described has the parts thereof designated by similar but primed reference numerals, in order to avoid repetition of description thereof.

10 The supporting-tube of the outer connector is arranged to be secured in an annular flange 22' of a flange-piece 23' provided with a laterally extending annular attaching wing 24', by means of which the flange-piece 15 is secured to the casing of the lamp by suitable means, as by soldering, brazing, or heat-welding. The set-screw 74' is threaded through a threaded hole in the flange 22' and clamps the socket-tube 25' in place. The 20 annular flange 22' may be provided with a slot 80 registering with the slot 73' for accommodating the flexible electric conductor 67.

The parts of this last-named connector, 25 may, for convenience, be designated as front and rear parts, similar to the designations applied with reference to the connector to which the electric light-bulb is arranged to be secured.

30 Having thus fully described my invention, what I claim as new and desire to secure by Letters Patent, is:

1. An electric connector of the character described comprising a socket-tube, a hard fiber washer of substantially equal thickness throughout and of substantially less thickness than diameter in said tube, an electric terminal post having its major portion outside said hard fiber washer at one side of 35 said washer and having resilient lengthwise movement in said hard fiber washer, said electric terminal post extending through said washer and provided with securing means for an electric conductor outside the other 40 side of said washer, and plug-securing means at one end of said tube whereby the electric terminal of said plug is held in contact with said post, and portions of said tube projecting inwardly in close adjacency to each 45 other across the ends of said hard fiber washer for compressing said hard fiber washer fixedly between said portions in end-wise relation in said tube.

2. An electric connector of the character described comprising a tube having plug-securing means thereon including a bayonet connection at the end of said tube for a bayonet plug having an annular periphery, said

plug-securing means comprising a normally substantially cylindrical tube-section having 60 a resilient tube portion free of attachment at its front and rear ends with said tube-section and integral at one of its lateral ends with said tube-section and extending in curved form inwardly within the longitudinal projection of said tube-section laterally about the plug position and arranged to be resiliently pushed outwardly by said plug when inserted in said plug-securing means.

3. An electric connector of the character 70 described comprising a socket-tube, a hard fiber washer of substantially equal thickness throughout and of substantially less thickness than diameter secured to said tube, an electric terminal post having lengthwise resilient movement through said hard fiber washer having its major portion outside said hard fiber washer, said socket-tube having plug-securing means thereon including a bayonet connection at the end of said socket- 75 tube for a bayonet plug having a substantially annular periphery, said plug-securing means comprising a resilient socket-tube portion free of attachment at its front and rear ends with said socket-tube and integral at 80 one of the lateral ends with said socket-tube section and extending in curved form laterally about the plug position and arranged to be resiliently pushed outwardly by said plug when inserted in said plug-securing 85 means.

4. The combination, in an electric connector, of a tube having a substantially cylindrical socket-section provided with opposite slots arranged lengthwise of said tube and 90 opening at the outer end of said tube and having hook-portions in one of the walls of said slots arranged for receiving the pins of a substantially annular electric plug, the other of the walls of said slots being formed 95 on laterally extending wings curved to conform to said substantially annular plug and which are free at their front and rear edges and integral with said socket-section at one 100 of their lateral edges, said wings being 105 curved inwardly within the longitudinal projection of said socket-section and arranged to be pressed outwardly by said plug, for the purpose described.

In testimony whereof, I have hereunto 110 signed my name in the presence of two subscribing witnesses.

CHARLES H. FISCHER.
